US00D998743S

(12) United States Design Patent (10) Patent No.: US D998,743 S
Burstein (45) Date of Patent: * Sep. 12, 2023

(54) MULTI-SHOT FIREARM SPEEDLOADER KNOB

(71) Applicant: Makershot LLC, Houston, TX (US)

(72) Inventor: Matthew Burstein, Cleveland Heights, OH (US)

(73) Assignee: Makershot LLC, Houston, TX (US)

() Term: 15 Years

(21) Appl. No.: 29/876,695

(22) Filed: May 26, 2023

(51) LOC (14) Cl. 22-01
U.S. Cl.

USPC D22/108; D8/307; D22/199

(58) Field of Classification Search
USPC D8/307; D22/108, 199
CPC F41A 9/85; Y10S 224/931
See application file for complete search history.

(57) CLAIM

The ornamental design for a multi-shot firearm speedloader knob, as shown and described.

DESCRIPTION

FIG. 1 is a perspective top view of a multi-shot firearm speedloader knob showing the claimed design;

FIG. 2 is a perspective bottom view thereof;

FIG. 3 is a side elevation view thereof;

FIG. 4 is a top view thereof;

FIG. 5 is a bottom view thereof; and,

FIG. 6 is a perspective top view thereof with environment. The broken lines in the figures represent portions of the multi-shot firearm speedloader knob or environmental structure that form no part of the claimed design.

1 Claim, 6 Drawing Sheets
